(57) **CLAIM**

The ornamental design for packaging for bicycle bar grips, as shown and described.

DESCRIPTION

FIG. 1 is a perspective view showing a first embodiment of my new design for a packaging for bicycle bar grips;

FIG. 2 is a front view of the packaging for bicycle bar grips of FIG. 1;

FIG. 3 is a rear view of the packaging for bicycle bar grips of FIG. 1;

FIG. 4 is a top view of the packaging for bicycle bar grips of FIG. 1;

FIG. 5 is a bottom view of the packaging for bicycle bar grips of FIG. 1;

FIG. 6 is a first side view of the packaging for bicycle bar grips of FIG. 1; and,

FIG. 7 is a second, opposite side view of the packaging for bicycle bar grips of FIG. 1.

The claimed design includes a second embodiment that is a mirror image of that shown in the drawings.
